UNITED STATES PATENT OFFICE

JOSEF BÄHNER, OF ATTENDORN IN WESTFALIA, GERMANY, ASSIGNOR TO THE FIRM
VEREINIGTE STAHLWERKE AKTIENGESELLSCHAFT, OF DÜSSELDORF, GERMANY

APPARATUS FOR ROLLING SHEET METAL

Application filed February 20, 1930, Serial No. 430,045, and in Germany July 18, 1929.

The present invention relates to a means for rolling annular ribs and corrugations into the walls of sheet-metal containers or the like which has decided advantages over the apparatus now in use. Heretofore, when a sheet-metal container, for example a steel barrel, had to be provided with reinforcing corrugations and rolling hoops or ribs, two different machines and consequently two steps had been necessary for the said purpose: by means of the first machine the annular corrugations having been rolled in by means of collars and grooves which were arranged on two parallel shafts and brought into complementary engagement during the rolling operation, whereas the similarly disposed shafts of the second machine were provided with hoop-rolls which were brought into complementary engagement during rolling and by means of which the rolling hoops were rolled into the wall of the container.

The present invention avoids these relatively troublesome proceedings using two machines by disposing the grooves or rings respectively for the production of the reinforcing corrugations as well as the hoop-rolls for the production of the rolling hoops on a common shaft. By this arrangement only one machine with two shafts disposed in parallelism to each other and carrying the above-mentioned devices will be necessary by means of which by a single-step operation the corrugations as well as the rolling hoops may be produced. According to the invention the rolling of the hoops is effected in such a way that the hoop-rolls of one shaft enter the correspondingly shaped hoop-rolls of the other shaft laterally. This is accomplished by arranging the laterally engaging hoop-rolls in a way that will allow for adjustment in axial direction and by subjecting them to the action of a spring which forces them into a position out of alinement relative to the hoop-rolls of the other shaft.

The advantage of this arrangement consists in that here the hoop-rolls of the two shafts are gradually brought into cooperative engagement whereby the wall of the container to be provided with rolling hoops will not be subjected to stresses as great as they

occur in the present practice and its thickness will remain the same overall.

The annexed drawing shows by way of example one embodiment of the machine according to the invention.

In this construction two shafts 1 and 2 are provided, one above the other, each having integral collars 3 and grooves 4 which are brought into complementary engagement during rolling for the purpose of producing the reinforcing corrugations. Intermediate these collars 3 and grooves 4 two hoop-rolls 5 are provided at the middle of each of the shafts 1 and 2 for the purpose of rolling the hoops. Whereas, however, the rolls 5 of shaft 1 are rigidly secured to the shaft, the rolls 5 of shaft 2 which are mounted on sliding sleeves 6 may be moved in axial direction. By means of a spiral spring 7 inserted between these two rolls, the latter are pressed against the front parts 8 of the shaft 2 and, consequently, into a position out of alinement with respect to the rolls 5 of shaft 1. The rigidity of the mounting of the rollers 5 on the shaft 1 is obtained by grooving said shaft 1 as indicated at 1^a and locating the rolls 5 in the grooves. The hub-like sleeve portions 6 of the rolls 5 of the lower shaft, however, are mounted to slide axially on said shaft 2 and, in the position of rest, they are pressed by the spring 7 against the front surfaces or shoulders 8. In this position, the rolls 5 of the upper and lower shafts are displaced relatively to one another a distance which is indicated at d on the drawing. Thus one succeeds in causing the rolls 5 of shaft 2 to enter the rolls 5 of shaft 1, which are provided with suitably shaped grooves, gradually during the rolling operation, against the action of spring 7 which at the same time secures a uniform cooperative engagement of all the rolls 5. Since the material of the container, as a result of the movability of the lower hoop-rolls, is drawn uniformly from both sides, the wall thickness of the container remains the same overall. Simultaneously with this operation, reinforcing ribs are rolled into the container by the collars 3 and grooves 4, the depth of said

grooves, however, being less than the depth of the collars formed by the rolls 5.

When the rolling is completed the rolls 5 of the shaft 2 are forced back into their original position by the action of spring 7.

Having thus described my invention what I claim as new and desire to secure by Letters Patent is:

1. Means for rolling two corrugations in
10 to sheet metal such as walls of containers, comprising two pairs of rolls arranged to receive the sheet metal, a shaft, one pair of said rolls being provided with grooves and being rigid on said shaft, a second shaft, the
15 other pair of rolls being provided with collars shaped to engage in the grooves of the first-mentioned rolls and being axially movable on the second shaft, the first and second mentioned pairs of rolls being relatively
20 displaced in the axial direction, a spring arranged to force the rolls on the second mentioned shaft into the displaced positions, said shafts being arranged parallel and said pairs of rolls being adapted to be brought into
25 complementary engagement, the rolls provided with collars moving axially in opposite directions against the tension of said spring and entering into the grooved rolls.

2. Means for rolling two corrugations in
30 to sheet metal such as walls of containers, comprising two pairs of rolls arranged to receive the sheet metal, a shaft, one pair of said rolls being provided with grooves and being rigid on said shaft, a second shaft, the
35 other pair of rolls being provided with collars shaped to engage in the grooves of the first-mentioned rolls and being axially movable on the second shaft, the first and second mentioned pairs of rolls being relatively
40 displaced in the axial direction, a spring arranged to force the rolls on the second mentioned shaft into the displaced positions, said shafts being arranged parallel and said pairs of rolls being adapted to be brought into
45 complementary engagement, the rolls provided with collars moving axially in opposite directions against the tension of said spring and entering into the grooved rolls, and additional collars and grooves on said shafts
50 adapted to cooperate with one another and being of less depth than the first-mentioned grooves and collars.

JOSEF BÄHNER.
